TIRE TREAD GAUGE

Robert J. Slavsky, Detroit, Mich., assignor to Shaw & Slavsky, Inc., Detroit, Mich.

Filed June 20, 1960, Ser. No. 61,046

Term of patent 14 years

(Cl. D52—1)

Fig. 1 is a front elevational view of a tire tread gauge showing my new design, the opposite side being substantially the same in appearance.

Fig. 2 is a bottom plan view thereof.

In Fig. 1, the shading in the left upper side is for red, the shading for the bottom is for amber or yellow, and the shading at the right upper side represents green.

I claim:

The ornamental design for a tire tread gauge, as shown and described.
